J. B. GARDNER.
SUPPLEMENTAL CAR STEP.
APPLICATION FILED JULY 9, 1914.

1,117,368.

Patented Nov. 17, 1914.

2 SHEETS-SHEET 2.

UNITED STATES PATENT OFFICE.

JOSEPH B. GARDNER, OF NORTH McALESTER, OKLAHOMA.

SUPPLEMENTAL CAR-STEP.

1,117,368.

Specification of Letters Patent. Patented Nov. 17, 1914.

Application filed July 9, 1914. Serial No. 849,983.

To all whom it may concern:

Be it known that I, JOSEPH B. GARDNER, a citizen of the United States, residing at North McAlester, in the county of Pittsburg and State of Oklahoma, have invented certain new and useful Improvements in Supplemental Car-Steps; and I do declare the following to be a full, clear, and exact description of the invention, such as will enable others skilled in the art to which it appertains to make and use the same.

My invention relates to improvements in supplemental car steps and more particularly to those having means for moving the same directly toward or away from the lowermost of the flight of steps to which they are applied.

The primary object of the invention is to provide a pressure projected step with a pressure operated catch whereby said catch will normally operate to retain the step in raised position but will be released by the operation of a valve to admit air into the cylinder employed for projecting or lowering said step.

A secondary object of the invention is to locate said pressure operated catch in such a manner as to allow the same and its coacting parts to be readily applied.

A further object of the invention is to provide a simple structure for slidably supporting and operating the supplemental step.

With these objects in view, the invention resides in certain novel features of construction and combination herein described and claimed and shown in the drawings wherein:

Figure 1 is a detail side elevation of a portion of a railway car showing the application of my invention thereto; Fig. 2 is a rear side elevation of one of the flights of steps and illustrating a sectional view through the car platform; Fig. 3 is a vertical transverse section on the line 3—3 of Fig. 2, also showing cylinder in section; Fig. 4 is a similar view on the line 4—4 of Fig. 2; Fig. 5 is a perspective view of one of the guides and the parts directly connected therewith.

In the accompanying drawings, I have shown a portion of a railway car or coach C which is equipped with the usual platform P and flight of steps S, the latter including the usual side boards B which are here shown as extending rearwardly from the

steps proper, this provision being made for a purpose to appear.

Rigidly secured to the rearwardly extending edge of one of the boards B is an inclined guide 1 which is here shown of elongated rectangular formation and is provided with a rectangular bore 2 opening at its lower end, with a longitudinal slot 3 which likewise opens at its lower end, with a pair of attaching ears 4 through which bolts 5 are passed to secure the device to the board B and with an opening 6 in one edge through which an inwardly projecting end 7 of an angular catch member 8 is adapted to slide, said member rising above the guide 1 and being integrally connected to a piston rod 9 whose inner end carries a piston 10 which is located in a cylinder 11, the latter being here shown as provided with attaching feet 12 which are rigidly secured to the upper end of said guide member 1. As clearly shown in the drawings, (see more particularly Fig. 3) a suitable coil spring 13 is provided within the cylinder 11 for normally retracting the piston and thereby projecting the active end 7 of the catch 8.

Located on the rearwardly extending portion of the remaining board B is a guide 1' which is provided with a longitudinal rectangular bore 2' and with a slot 3', the bore and slot opening through its lower end. The guide 1' is further provided with attaching ears 4' which are designed for the same purpose as the ears 4 previously described.

Slidably mounted within the guides 1 and 1' is a pair of inclined guide arms 14 and 14', the arm 14 being located in the guide 1 while the arm 14' is disposed in the guide 1'. As most clearly seen in Figs. 2, 3 and 5, the arms 14 and 14' are provided with enlarged rectangular portions 15 and 15' which slidably engage the walls of the bores 2 and 2'.

The enlarged portion 15 of the arm 14 is provided in one edge, with a notch 16 which is located near its upper end, the corner of said portion 15, directly above said notch, being rounded as at 17 for engagement with the extreme inner end of the active portion 7 of the catch 8, whereby said catch will be retracted against the tension of its spring when said arm 14 is raised, thereby allowing said spring to force the active end 7 of said catch 8 into said notch 16 to retain said arm in raised position.

The arms 14 and 14' are provided with

horizontally extending lower end portions 18 to which the opposite ends of a supplemental step 19 are secured, said step lying directly beneath the lowermost of the flight

5 S. Said arms are further connected, near their upper ends, by a bar 20 which is rigidly secured thereto and which slides loosely within the slots 3 and 3', a piston rod 21 being secured to said bar 20 and carrying a piston 22 upon its upper end, the latter being located in a cylinder 23 supported beneath the steps S in any suitable manner. A coil spring 24 is preferably interposed between the piston 22 and the lower

15 end of the cylinder, said spring acting to normally retract or raise the step 19 and the parts carried thereby.

Leading from a source of supply, such as the ordinary train pipe (not shown), is 20 a pressure supply pipe 25 which discharges into the cylinder 11 in rear of its piston 10, while a second pressure supply pipe 26 extends from the intermediate portion of said cylinder 11 to the upper end of the cylinder 23, this positioning and arrangement of parts causing the piston 10 to be projected for the purpose of retracting the catch 8, when the pressure is allowed to pass through the pipe 25 by the operation of a valve (not shown), this movement on the part of the piston 10 allowing the adjacent ends of the pipes 25 and 26 to communicate, thus allowing the pressure to flow through the cylinder 11 and the pipe 26 into the upper end of

35 the cylinder 23 at which point it will act to force the piston 22 downwardly against the tension of the spring 24, thereby through the provision of the operating bar 20 and the arms 14 and 14', lowering or projecting the

40 step.

As long as the above mentioned valve remains open, it will be seen that the step will remain in lowered position. When, however, the valve is closed, the tension of

45 the spring 24 returns the step to normal

position upon which movement, the catch 8,

is again engaged with the notch 16 by its

spring 13. It may here be explained, that

50 during the upward movement of the piston

22, the air in the cylinders 23 and 11 will

be forced through the pipes 26 and 25 to the

valve which is provided with an exhaust

55 port as is common with devices of this

character.

55 From the above description, taken in connection with the accompanying drawings, it will be seen that I have produced an extremely simple device of the character set forth, yet one which will be highly efficient

60 in operation and which will readily carry out the objects of the invention.

Particular emphasis is laid upon the provision of the pressure operated catch in connection with the cylinder and piston for projecting the supplemental step, since, by this

arrangement of parts, it will be seen that said step is positively held in retracted position until it is desired to lower the same upon which action the catch is first released after which pressure is exerted in said cylinder to 70 lower the step.

Having thus described my invention, what I claim as new and desire to secure by Letters Patent is:

1. The combination with the lowermost of 75 a flight of steps, of a supplemental step mounted beneath the same to move toward and away therefrom, a pressure released catch mechanism mounted above said supplemental step, a keeper operable with said supplemental step and adapted to receive said catch when the step is raised, pressure operated means for lowering said supplemental step, a pressure supply pipe for said catch mechanism, and a similar pipe continuing therefrom to said pressure operated means.

2. The combination with the lowermost of 80 a flight of steps, of a supplemental step mounted beneath the same to move toward and away therefrom, a pressure released catch mechanism mounted above said supplemental step, a keeper operable with said supplemental step and adapted to receive said catch when the step is raised, a cylinder 85 and piston for lowering said step, a pressure supply pipe for said catch mechanism, and a similar pipe continuing therefrom to said cylinder.

3. The combination with the lowermost of 90 a flight of steps, of a supplemental step movable toward and away therefrom, a keeper operable with said supplemental step, a catch coacting with said keeper for securing the step in raised position, said catch 95 having an operating piston, a cylinder receiving the same, a cylinder and piston for lowering the supplemental step, a pressure supply pipe leading to the catch operating cylinder, and a similar pipe leading there-

100 from to the step operating cylinder.

4. The combination with the lowermost of 105 a flight of steps, of a supplemental step movable toward and away therefrom, a keeper operable with said supplemental step, a spring projected catch coacting with said keeper for securing the supplemental step in raised position, said catch having a retracting piston, a cylinder receiving the same, a

110 cylinder and piston for lowering the supplemental step, the latter being normally raised, a pressure supply pipe leading to the catch operating cylinder, and a similar pipe leading therefrom to the step projecting cylinder.

5. The combination with a flight of steps, 115 of an inclined guide secured adjacent the same, a guide arm slidably in said guide and having a shoulder, a supplemental step secured to the lower end of said arm and lying 120

125 130

beneath the lowermost of said flight of steps, a cylinder and piston for lowering said supplemental step, the same being normally raised, a catch operating cylinder, a normally projected catch coacting with said shoulder for retaining the step in raised position, said catch having a retracting piston located in said catch operating cylinder, a pressure supply pipe leading to the last mentioned cylinder, and a similar pipe leading therefrom to the step operating cylinder.

6. The combination with a flight of steps and a supplemental step beneath the lowermost thereof, of an inclined guide adjacent said flight, a guide arm slideable in said guide and attached to said supplemental step, said arm having a rounded nose, an angular catch coacting with said nose for retaining the step in raised position, a piston on said catch, a cylinder receiving said piston and mounted on said guide, a spring for projecting said catch and a pressure supply pipe to said cylinder.

7. The combination with a flight of steps and a supplemental step beneath the same,

of an inclined guide secured adjacent said flight and having a bore opening through its lower end and a slot opening into said bore, a guide arm slideable in said bore and having a rounded nose on its upper end, an angular catch member sliding through an aperture in one side of the guide and coacting with said nose for retaining said arm in raised position, its lower end being secured to said supplemental step, a cylinder mounted on the upper end of said guide, a piston therein and having a connection with said angular catch member, a spring for projecting the latter, a pressure supply pipe for said cylinder, an operating bar secured to said arm and projecting through said slot and means connected to said bar for lowering said supplemental step.

In testimony whereof I have hereunto set my hand in presence of two subscribing witnesses.

JOSEPH B. GARDNER.
